UNITED STATES PATENT OFFICE.

NICOLAUS A. OTTO, OF DEUTZ-ON-THE-RHINE, PRUSSIA, GERMANY.

GAS-MOTOR ENGINE.

SPECIFICATION forming part of Letters Patent No. 288,478, dated November 13, 1883.

Application filed May 3, 1883. (No model.) Patented in England April 3, 1883, No. 1,677.

To all whom it may concern:

Be it known that I, NICOLAUS AUGUST OTTO, a citizen of Prussia, residing at the Gas-Motoren-Fabrik-Deutz, at Deutz-on-the-Rhine, in the German Empire, have invented a new and useful Improvement in Gas-Motor Engines, (for which provisional protection has been obtained in Great Britain, No. 1,677, dated April 3, 1883,) of which the following is a specification.

My invention has for its object to produce a very uniform or equable motion in single-acting gas-motor engines—that is to say, those in which the admission and ignition of a combustible gaseous charge take place on one side only of the piston.

The invention consists in causing the power produced by the combustion of a gaseous charge to be partially expended during the outstroke of the piston in increasing the compression of air which has already previously been compressed to a certain extent, and which is allowed to expand again on the return-stroke of the piston, thus giving out the power previously stored up.

Various arrangements may be employed for carrying out the invention. In the arrangement employed, by preference, there is provided, in combination with the engine, a closed receiver or chamber, in which air is, in the first instance, compressed to a certain degree by a hand-pump, or other suitable means, so that at the commencement of the working out-stroke of the piston, when the expansive force of the combustion-gases is greatest, there shall be opposed to it a considerable resistance in causing it to effect the further compression of the already compressed air in the receiver. The compression of the air may be effected either directly by the working-piston, by closing the front end of the cylinder and establishing a communication between the front end and the compressed-air receiver, so that the air in front of the piston, being under the same pressure as that existing in the receiver, will be forced back into the latter; or the front end of the cylinder may be open, as usual, and a second cylinder be provided, which communicates with the air-receiver, and whose piston is connected to the crank-

shaft in such manner that when the working-piston is performing its outstroke the piston in the auxiliary cylinder is caused to force the air from the latter into the receiver, while on the return stroke of the working-piston the compressed air, in expanding in the auxiliary cylinder, moves its piston, so as to transmit the power thus given off to the crank-shaft. In employing this arrangement it is convenient to construct the engine with two working-cylinders, as shown at Fig. 1 of the accompanying drawings.

a and *b* are two working-cylinders, with pistons *a'* and *b'* connected to parallel cranks on the crank-shaft *c*. Between these is a third cylinder, *d*, with piston *d'* connected by a pipe, *f*, with the compressed-air reservoir *e*. The crank of the piston *d'* is diametrically opposite those of *a'* and *b'*, so that, when the latter alternately perform their working-outstroke on the combustion and expansion of a gaseous charge, the piston *d'* will be made to perform its instroke, forcing the air under pressure contained in the cylinder through the pipe *f* back into the reservoir *e*. On the return-stroke of the pistons *a'* *b'* the compressed air in *e* will force the piston *d'* outward, thus giving off the power again that was previously stored up.

k is a hand-pump for charging the reservoir with air of the required pressure in the first instance. A cock, *l*, is provided for preventing the escape of the air-pressure when the engine is not at work.

Fig. 2 shows a sectional plan of an arrangement in which the additional compressing-cylinder is dispensed with, the front end of the cylinder *b* being closed and connected directly by a pipe, *f*, with the reservoir *e*. The reservoir is also connected by a second pipe, *g*, provided with a check-valve, *h*, with an intermediate point in the length of the cylinder, by which arrangement any loss of pressure in the reservoir, due to leakage, is made good automatically at each working-outstroke of the piston, inasmuch as, when the piston passes beyond the opening of *g*, the gases under pressure contained behind it will enter *e* and raise the air therein to the same pressure. The check-valve *h* prevents such pressure from passing back again when, by the further expansion of the

gases, their pressure has decreased. By regulating the load on this valve the degree of pressure in the air-vessel will also be regulated. It will be evident that this arrangement could also be applied to the construction of engines shown at Fig. 1, by connecting either one or both cylinders *a b*, at an intermediate point of their length, with the air-reservoir *e* by a pipe provided with a check-valve.

10 From the foregoing description it will readily be seen that the unequal action of single-acting gas-motor engines will, by this invention, be effectually compensated and a comparatively uniform motion be obtained without the use of large and heavy fly-wheels. As is well understood, the explosion of the combustible charge of such engines develops very considerable force during the working-outstroke of the piston, resulting in a very rapid outward motion of the piston and correspondingly rapid semi-revolution of the crank-shaft, while the remainder of the revolution of the latter and the return-stroke of the piston can only be effected by the expenditure of the *vis viva* stored up in the shaft and fly-wheel during the outstroke. Hence it follows that, unless the fly-wheel be made inconveniently large and massive, so as to enable it to take up a large amount of *vis viva*, the return-stroke of the piston and second half of the revolution of the shaft will take place at a comparatively slow speed, the unsteady motion of the engine thus obtained rendering it unsuitable for work—such as driving dynamo-electric machines—requiring a very uniform motion. Now, by expending a portion of the power developed during the working-outstroke in compressing air in a reservoir or chamber, as above described, and then allowing the motive power thus stored up to be given off during the return-stroke of the piston, it will be very evident that the power developed by the engine will practically be

evenly distributed over the entire revolution of the engine-shaft, resulting in a greatly-increased uniformity of motion of the engine.

Having thus described the nature of my invention and the best means I know of carrying the same into practical effect, I claim—

1. In a gas-motor engine, in which the admission and combustion of gaseous charges takes place only at one side of the piston, the method of operating the same, which consists in expending a portion of the power produced by the combustion of the charge during the working-stroke of the piston, to increase the pressure of air which has been previously compressed to a certain degree, and afterward expanding said air upon the return-stroke of the piston, to apply the power stored up, substantially as described.

2. In combination with a gas-motor engine in which the admission and combustion of the gaseous charges take place on one side of the piston only, a compressed-air reservoir, the air in which is still further compressed during the working-outstroke of the engine-piston and expands again during the instroke of the engine-piston, substantially as and for the purpose herein described.

3. In a gas-motor engine, the combination of two single-acting cylinders, *a b*, whose pistons *a' b'* are connected to parallel cranks on the engine-shaft *c*, with a compressing-cylinder, *d*, whose piston *d'* is connected to a crank opposite to those of *a' b'*, and which is connected by a pipe, *f*, with a reservoir, *e*, for compressed air, substantially as herein described.

In testimony whereof I have signed my name to this specification, in the presence of two subscribing witnesses, this 13th day of April, A. D. 1883.

NICOLAUS AUGUST OTTO.
